WALL LUMINAIRE

Charles I. Rosen, Englewood, N.Y., assignor to Emerson
Electric Co., St. Louis, Mo., a corporation of Missouri

Filed July 1, 1965, Ser. No. 85,973

Term of patent 14 years

(Cl. D48—4)

Fig. 1

Fig. 2

Fig 3

Fig 4

FIGURE 1 is a substantially frontal view in perspective of one embodiment of wall luminaire of this new design showing dual back-mounted candelabra sockets and a central downwardly directed conical flood lamp reflector;

FIGURE 2 is a bottom plan view of the luminaire shown in FIGURE 1;

FIGURE 3 is a substantially frontal view in perspective of another embodiment of wall luminaire of this new design showing dual bottom mounted candelabra sockets and a central downwardly directed conical flood lamp reflector; and

FIGURE 4 is a substantially posterior view in perspective showing the planar back common to both embodiments.

The dominant features of my design reside in those portions shown in full lines.

I claim:

The ornamental design for a wall luminaire, substantially as shown and described.
